Primary Examiner — Kevin K Rudzinski*Assistant Examiner* — Evans David Delesline(74) *Attorney, Agent, or Firm* — PEARL COHEN
ZEDEK LATZER BARATZ LLP(57) **CLAIM**

The ornamental design for jewelry, as shown and described.

DESCRIPTION

- 1. Jewelry
- 1.1 : Perspective
- 1.2 : Perspective
- 1.3 : Front
- 1.4 : Back
- 1.5 : Right
- 1.6 : Left
- 1.7 : Top
- 1.8 : Bottom

The product incorporating the design is used as jewelry; the essential features of the design lay in its shape; the perspective view in figure 1.1 is designated to best show the essential features of the design; the broken lines in the drawings depict portions of the jewelry that form no part of the claimed design; the shading lines in the drawings represent contour only and do not illustrate ornamentation or decoration on the surface of the jewelry.

1 Claim, 8 Drawing Sheets(56)
